(57) **ABSTRACT**

A laundry or dryer appliance, as provided herein, may include a cabinet, a drum, a door, and an additive dispensing assembly. The drum may be mounted within the cabinet and define a space for the receipt of clothes. The door may be movably mounted to the cabinet to selectively restrict access to the drum. The additive dispensing assembly may be held on the door and configured to provide an additive mist to the drum. The additive dispensing assembly may include an additive tank, a fluid pump, and a dispenser nozzle. The additive tank may define a tank volume to store an additive therein. The fluid pump may be in fluid communication with the additive tank to motivate a volume of the additive. The dispenser nozzle may be directed toward the drum downstream from the fluid pump to guide the volume of the additive into the space defined by the drum.

FIG. 1

FIG. 2

FIG. 4

FIG. 8

FIG. 9

LAUNDRY APPLIANCE AND ADDITIVE DISPENSING ASSEMBLY

FIELD OF THE INVENTION

The present subject matter relates generally to laundry appliances, such as dryer appliances, and more particularly to additive dispensers for laundry appliances.

BACKGROUND OF THE INVENTION

Laundry appliances, such as dryer appliances, generally include a cabinet with a drum mounted therein. In some appliances, a motor rotates the drum during operation of the thereof (e.g., to tumble articles located within a chamber defined by the drum). Dryer appliances also generally include a heater assembly that passes heated air through the chamber of the drum in order to dry moisture-laden articles disposed within the chamber. This internal air then passes from the chamber through a vent duct to an exhaust conduit, through which the air is exhausted from the dryer appliance.

In some instances, it may be desirable to provide certain objects or fluids for the treatment of articles within an appliance. For instance, dryer sheets are commonly placed within the drum of a dryer appliance to affect the smell of the fabrics or clothes being treated (e.g., tumbled or dried) in a specific laundry load. In other instances, a wrinkle release fluid (e.g., fluids comprising fabric relaxer, fabric softener, isopropyl alcohol, vinegar, etc.) may be applied to sprayed on articles by a user before or after the articles are treated by the dryer appliance. In still other instances a UV fabric protector (e.g., fluids comprising titanium oxide, bemotrizinol, etc.) to absorb or repel ultraviolet light emissions may be sprayed on articles by a user before or after the articles are treated by the dryer appliance. However, difficulties exist with such approaches. Specifically, a user must generally remember to supply a specific object or fluid to each individual drying load. Moreover, in many cases a user must estimate or guess how much of the specific object or fluid is appropriate for an individual load. Although some existing dryer appliances provide for automatically (e.g., without direct user input) supplying steam to individual dryer loads, existing dryer appliances are generally unable to automatically supply specific additives to articles therein.

Accordingly, a laundry appliance having an additive dispensing assembly for delivering certain additives affecting the smell or performance of fabrics would be desirable. More particularly, a laundry appliance having an additive dispensing assembly that provides a suitable additive volume load across a range of applications would be especially desirable.

BRIEF DESCRIPTION OF THE INVENTION

Aspects and advantages of the invention will be set forth in part in the following description, or may be obvious from the description, or may be learned through practice of the invention.

In one exemplary aspect of the present disclosure, a dryer appliance is provided. The dryer appliance may include a cabinet, a drum, a door, and an additive dispensing assembly. The drum may be rotatably mounted within the cabinet. The drum may define a space for the receipt of clothes for drying. The door may be movably mounted to the cabinet to selectively restrict access to the drum. The additive dispensing assembly may be held on the door and configured to provide an additive mist to the drum. The additive dispens-

ing assembly may include an additive tank, a fluid pump, and a dispenser nozzle. The additive tank may define a tank volume to store a dryer additive therein. The fluid pump may be in fluid communication with the additive tank to motivate a volume of the dryer additive therefrom. The dispenser nozzle may be directed toward the drum downstream from the fluid pump to guide the volume of the dryer additive into the space defined by the drum.

In another exemplary aspect of the present disclosure, a laundry appliance is provided. The laundry appliance may include a cabinet, a drum, a door, and an additive dispensing assembly. The drum may be rotatably mounted within the cabinet. The drum may define a space for the receipt of clothes. The door may be movably mounted to the cabinet to selectively restrict access to the drum. The additive dispensing assembly may include an additive tank, a fluid pump, a dispenser nozzle, and a one-way valve. The additive tank may define a tank volume to store a liquid additive therein. The additive tank may be removably mounted within the internal cavity. The fluid pump may be in fluid communication with the additive tank to motivate a volume of the liquid additive therefrom. The dispenser nozzle may be directed toward the drum downstream from the fluid pump to guide the volume of the liquid additive into the space defined by the drum. The one-way valve may be in fluid communication between the additive tank and the dispenser nozzle to permit the volume of liquid additive to the dispenser nozzle from the additive tank.

These and other features, aspects and advantages of the present invention will become better understood with reference to the following description and appended claims. The accompanying drawings, which are incorporated in and constitute a part of this specification, illustrate embodiments of the invention and, together with the description, serve to explain the principles of the invention.

BRIEF DESCRIPTION OF THE DRAWINGS

A full and enabling disclosure of the present invention, including the best mode thereof, directed to one of ordinary skill in the art, is set forth in the specification, which makes reference to the appended figures.

FIG. 1 provides a perspective view of a laundry appliance provided as a dryer appliance in accordance with exemplary embodiments of the present disclosure.

FIG. 2 provides a perspective view of the exemplary dryer appliance of FIG. 1 with portions of a cabinet of the dryer appliance removed to reveal certain components of the dryer appliance.

FIG. 3 provides a perspective view of a door, in isolation, of a laundry appliance according to exemplary embodiments of the present disclosure.

FIG. 4 provides a perspective of the exemplary door of FIG. 3 with various components removed to reveal certain portions of the door.

FIG. 5 provides a schematic rear elevation view of the exemplary door of FIG. 3.

FIG. 6 provides a schematic view of the additive dispensing assembly of the exemplary door of FIG. 3.

FIG. 7 provides a perspective view of a door, in isolation, of a laundry appliance according to exemplary embodiments of the present disclosure.

FIG. 8 provides a perspective of the exemplary door of FIG. 7 with various components removed to reveal certain portions of the door.

FIG. 9 provides a schematic front elevation view of the exemplary door of FIG. 7.

FIG. 10 provides a perspective view of an additive tank of an additive dispensing assembly according to exemplary embodiments of the present disclosure.

DETAILED DESCRIPTION

Reference now will be made in detail to embodiments of the invention, one or more examples of which are illustrated in the drawings. Each example is provided by way of explanation of the invention, not limitation of the invention. In fact, it will be apparent to those skilled in the art that various modifications and variations can be made in the present invention without departing from the scope of the invention. For instance, features illustrated or described as part of one embodiment can be used with another embodiment to yield a still further embodiment. Thus, it is intended that the present invention covers such modifications and variations as come within the scope of the appended claims and their equivalents.

As used herein, the term "or" is generally intended to be inclusive (i.e., "A or B" is intended to mean "A or B or both"). The terms "first," "second," and "third" may be used interchangeably to distinguish one component from another and are not intended to signify location or importance of the individual components. The terms "upstream" and "downstream" refer to the relative flow direction with respect to fluid flow in a fluid pathway. For example, "upstream" refers to the flow direction from which the fluid flows, and "downstream" refers to the flow direction to which the fluid flows. The term "clothing" includes but need not be limited to fabrics, textiles, garments, linens, papers, or other items from which the extraction of moisture is desirable. Furthermore, the term "load" or "laundry load" refers to the combination of clothing that may be washed together in a washing machine or dried together in a dryer appliance (e.g., clothes dryer) and may include a mixture of different or similar articles of clothing of different or similar types and kinds of fabrics, textiles, garments and linens within a particular laundering process.

Turning now to the figures, FIG. 1 provides a laundry appliance (e.g., dryer appliance 10) according to exemplary embodiments of the present disclosure. FIG. 2 provides another perspective view of dryer appliance 10 with a portion of a cabinet or housing 12 of dryer appliance 10 removed in order to show certain components of dryer appliance 10. Dryer appliance 10 generally defines a vertical direction V, a lateral direction L, and a transverse direction T, each of which is mutually perpendicular, such that an orthogonal coordinate system is defined. While described in the context of a specific embodiment of dryer appliance 10, using the teachings disclosed herein, it will be understood that dryer appliance 10 is provided by way of example only. Other laundry appliances, such as a washing machine appliance (e.g., front-load washing machine) or other dryer appliances having different appearances and different features, may also be used with the present subject matter as well.

Cabinet 12 includes a front panel 14, a rear panel 16, a pair of side panels 18 and 20 spaced apart from each other by front and rear panels 14 and 16, a bottom panel 22, and a top cover 24. Within cabinet 12 is a drum or container 26 mounted for rotation about a substantially horizontal axis. Drum 26 defines a chamber 25 for receipt of articles of clothing (e.g., for tumbling or drying). Drum 26 extends between a front portion 37 and a back portion 38. Drum 26 also includes a back or rear wall 34 (e.g., at back portion 38

of drum 26). A supply duct 41 is mounted to rear wall 34 and receives heated air that has been heated by a heating assembly or system 40.

5 A motor 31 is provided in some embodiments to rotate drum 26 about the horizontal axis (e.g., via a pulley and a belt—not pictured). Drum 26 is generally cylindrical in shape, having an outer cylindrical wall 28 and a front flange or wall 30 that defines an opening 32 of drum 26 (e.g., at front portion 37 of drum 26) for loading and unloading of articles into and out of chamber 25 of drum 26. A plurality 10 of lifters or baffles (e.g., baffles 27) are provided within chamber 25 of drum 26 to lift articles therein and then allow such articles to tumble back to a bottom of drum 26 as drum 26 rotates. Baffles 27 may be mounted to drum 26 such that 15 baffles 27 rotate with drum 26 during operation of dryer appliance 10.

20 Motor 31 may also be in mechanical communication with an air handler 48 such that motor 31 rotates a fan 49 (e.g., a centrifugal fan) of air handler 48. Air handler 48 is 25 configured for drawing air through chamber 25 of drum 26 (e.g., in order to dry articles located therein). In alternative exemplary embodiments, dryer appliance 10 may include an additional motor (not shown) for rotating fan 49 of air handler 48 independently of drum 26.

25 Drum 26 is generally configured to receive heated air that has been heated by a heating assembly 40 (e.g., in order to dry damp articles disposed within chamber 25 of drum 26). For example, heating assembly 40 may include a heating element (not shown), such as a gas burner, an electrical 30 resistance heating element, or heat pump, for heating air. As discussed above, during operation of dryer appliance 10, motor 31 rotates drum 26 and fan 49 of air handler 48 such that air handler 48 draws air through chamber 25 of drum 26 when motor 31 rotates fan 49. In particular, ambient air 35 enters heating assembly 40 via an inlet 51 due to air handler 48 urging such ambient air into inlet 51. Such ambient air is heated within heating assembly 40 and exits heating assembly 40 as heated air. Air handler 48 draws such heated air through supply duct 41 to drum 26. The heated air enters 40 drum 26 through a plurality of outlets of supply duct 41 positioned at rear wall 34 of drum 26.

Within chamber 25, the heated air may accumulate moisture (e.g., from damp clothing disposed within chamber 25). In turn, air handler 48 draws moisture saturated air through 45 a screen filter (not shown) which traps lint particles. Such moisture saturated air then enters an exit duct 46 and is passed through air handler 48 to an exhaust duct 52. From exhaust duct 52, such moisture saturated air passes out of dryer appliance 10 through a vent 53 defined by cabinet 12. After 50 the clothing articles have been dried, they may be removed from the drum 26 via opening 32. A door 33 mounted to cabinet 12 provides for closing or accessing drum 26 through opening 32.

55 One or more selector inputs 70, such as knobs, buttons, touchscreens, etc., may be provided or mounted on a cabinet backsplash 71 and is in operable communication (e.g., electrically coupled or coupled through a wireless network band) with a processing device or controller 56. Signals generated in controller 56 direct operation of motor 31 and heating assembly 40 in response to the position of 60 selector knobs 70. Alternatively, a touch screen type interface may be provided. As used herein, "processing device" or "controller" may refer to one or more microprocessors, microcontroller, ASICs, or semiconductor devices and is not 65 restricted necessarily to a single element. The controller 56 may be programmed to operate dryer appliance 10 by executing non-transitory instructions stored in memory. The

controller 56 may include, or be associated with, one or more memory elements such as RAM, ROM, or electrically erasable, programmable read only memory (EEPROM). For example, the instructions may be software or any set of instructions that when executed by the processing device, cause the processing device to perform operations.

Referring now to FIGS. 3 through 6, a door 200 and additive dispensing assembly 202 are illustrated according to exemplary embodiments of the present disclosure. Specifically, FIGS. 3 through 5 provide various views of a door 200 (e.g., provided as or as part of door 33) to a laundry appliance (e.g., dryer appliance 10). FIGS. 5 and 6 illustrate portions of additive dispensing assembly 202 both within door 200 (FIG. 5) and in isolation (FIG. 6) for clarity. Although the discussion below refers to additive dispensing assembly 202, one skilled in the art will appreciate that the features and configurations described may be used for other additive dispensers in other dryer appliances as well. For example, additive dispensing assembly 202 may be positioned elsewhere within door 200; may have a different components or configurations; or may dispense water, detergent, or other additives. It is understood that other variations and modifications of the exemplary embodiments described below are possible, and such variations are contemplated as within the scope of the present subject matter.

As shown, door 200 generally includes an exterior surface 204 and an interior surface 206 spaced apart from each other along the transverse direction T (e.g., as defined when door 200 is in a closed position restricting access to drum 26, such as the position illustrated in FIG. 1). As is understood, when door 200 is rotatably or pivotably mounted on cabinet 12, exterior surface 204 is directed away from the drum 26 while interior surface 206 is directed toward drum 26. Thus, exterior surface 204 is distal to drum 26, and interior surface 206 is proximal to drum 26. In some such embodiments, at least a portion of exterior surface 204 is defined by an outer panel 208 (e.g., comprising an air-impermeable metal, glass, or polymer), and at least a portion of interior surface 206 is defined by an inner panel 210 (e.g., comprising an air-impermeable metal, glass, or polymer) that is joined to (e.g., separably as discrete elements or, alternatively, integrally as a unitary element with) the outer panel 208.

Between exterior surface 204 and interior surface 206, an internal cavity 212 is defined. For instance, a discrete assembly panel 214 may be attached to inner panel 210. Assembly panel 214 may form internal cavity 212 within itself or with at least a portion of inner panel 210. When assembled, assembly panel 214 may extend generally inward toward drum 26 (e.g., from a recessed or planar portion of inner panel 210), thereby forming an internally protruding swell of interior surface 206 within which internal cavity 212 is defined. An opening 220 defined through interior surface 206 (e.g., through assembly panel 214) may permit a user to selectively access internal cavity 212 when door 200 is in an open position (or otherwise not fully closed).

In certain embodiments, a movable or removable flap 222 is provided and selectively covers the opening 220 to internal cavity 212. For instance, as would be understood, flap 222 can be moved (e.g., pivoted, slid, or detached from assembly panel 214) to an uncovered position apart from the opening 220. Thus, flap 222 can permit access to internal cavity 212 in the uncovered position. By contrast, in the covered position (e.g., shown in FIG. 3), flap 222 restricts access to internal cavity 212 such that a user may be unable to pass a hand or object through opening 220 to internal cavity 212.

As shown, an additive dispensing assembly 202 is held on door 200. For instance, at least a portion of additive dispensing assembly 202 may be mounted within internal cavity 212. As will be described in detail below, additive dispensing assembly 202 includes an additive tank 228, fluid pump 232, and dispenser nozzle 234, all in fluid communication with each other to selectively dispense an additive mist to drum 26.

In some embodiments, one or more portions of additive dispensing assembly 202 (e.g., additive tank 228 or fluid pump 232) are secured within internal cavity 212 via a plurality of mounting features or mechanical fasteners. Additionally or alternatively, adhesive(s), snap-fit mechanisms, interference-fit mechanisms, or any suitable combination thereof may secure one or more portions of additive dispensing assembly 202 to door 200. One skilled in the art will appreciate that additive dispensing assembly 202 may be mounted to door 200 using other mounting means according to alternative embodiments.

Generally, additive tank 228 is mounted upstream from dispenser nozzle 234 to retain a liquid additive (e.g., dryer additive) that may be dispensed to drum 26 through dispenser nozzle 234. Thus, one or more suitable fluid conduits or pipes may extend from additive tank 228 to dispenser nozzle 234. In certain embodiments, additive tank 228 defines a tank volume 230 within internal cavity 212, and within which a dryer additive may be poured. For instance, tank volume 230 may be provided as an isolated (e.g., non-plumbed) volume. Thus, a user may directly supply an additive (e.g., liquid dryer additive) to tank volume 230, which may then be used during operation of the respective appliance. Moreover, a user may directly refill the dryer additive by opening the door 200, opening the internal cavity 212 (e.g., by lifting flap 222), and accessing or removing additive tank 228 from internal cavity 212.

Generally, tank volume 230 may be sized to store sufficient amounts of dryer additives for multiple cycles in order to avoid requiring the user to add a measured quantity of dryer additive prior to each dryer cycle. Optionally, the dryer additive may include a perfume material to provide a desirable smell or scent to a dry load. Additionally or alternatively, the dryer additive may include a UV fabric protector (e.g., a fluid comprising titanium oxide, bemotrizinol, etc.) to absorb or repel ultraviolet light emissions. Also additionally or alternatively, the dryer additive may include a wrinkle release fluid (e.g., a fluid comprising fabric relaxer, fabric softener, isopropyl alcohol, vinegar, etc.) to reduce or prevent wrinkles from forming on articles within a dry load. Further additionally or alternatively, the dryer additive may include a medicinal liquid (e.g., antibacterial liquid, antiallergen, dermatitis-treatment liquid, burn-treatment liquid, insect repellent, topical cannabinoid, etc.). Moreover, it is noted that any other suitable dryer additive may be included.

As shown, fluid pump 232 is in fluid communication with additive tank 228. For instance, one or more suitable fluid conduits or pipes may extend from additive tank 228 to fluid pump 232 or, alternatively, from fluid pump 232 to additive tank 228.

In exemplary embodiments, fluid pump 232 is downstream from additive tank 228 to selectively motivate a volume (e.g., predetermined volume) of dryer additive from additive tank 228. In some such embodiments, a check valve or one-way valve (e.g., first one-way valve 236) is mounted in fluid communication between additive tank 228 and fluid pump 232. In other words, a first one-way valve 236 may be disposed along the fluid path or conduit extending from

additive tank 228 to fluid pump 232. First one-way valve 236 may thus ensure a unidirectional flow of dryer additive downstream from additive tank 228 (e.g., according to gravity or negative pressure generated at fluid pump 232).

Generally, fluid pump 232 may be provided as any suitable powered pump (i.e., not manually operated) to selectively force or motivate liquid or dryer additive from additive tank 228 to dispenser nozzle 234. In exemplary embodiments, fluid pump 232 includes a reciprocating pump assembly. For instance, fluid pump 232 may include a fluid cylinder 240 and a reciprocating piston 242 slidably disposed within cylinder 240. As shown, cylinder 240 may define a separate cylinder inlet 244 and cylinder outlet 246 through which liquid or dryer additive can enter and exit cylinder 240, respectively (e.g., according to the position of reciprocating piston 242 within cylinder 240). A pump motor 248 may be connected to or in mechanical communication with reciprocating piston 242 to control the position or movement of reciprocating piston 242 relative to cylinder 240. As an example, pump motor 248 may include a pinion gear 250 in mechanical communication with a rack gear provided on the piston rod 252 of reciprocating piston 242.

In additional or alternative embodiments, fluid pump 232 is electrically connected to a suitable power source 254 or controller 256 (e.g., provided separately or as part of controller 56—FIG. 1). For instance, the power source 254 and controller 256 may be connected to pump motor 248. Thus, fluid pump 232 may be generally controlled (e.g., selectively activated, as directed by the controller 256) to motivate a volume of liquid or dryer additive from additive tank 228. Optionally, one or both of power source 254 and controller 256 may be held on door 200 (e.g., within internal cavity 212 or otherwise apart from cabinet 12).

As an example, controller 256 or pump motor 248 may be in operable communication with controller 56 via a wired or wireless communications band, as would be understood. As an additional or alternative example, power source 254 (e.g., Direct Current power supply) may be in operable communication with controller 256 (or a separate power supply provided within cabinet 12—FIG. 1) via one or more wired, electrical connections (e.g., conductive wires or busses) or inductive connections. Optionally, power source 254 may be inductively coupled to a separate supply on cabinet 12. For instance, a transmitter induction coil 258 may be mounted to cabinet 12 proximal to door 200 (e.g., when door 200 is in the closed position). A separate receiver induction coil 260 may be mounted to door 200 in electrical communication with fluid pump 232 (e.g., indirectly through power source 254). When door 200 is in the closed position, transmitter induction coil 258 may initiate an electromagnetic field to be transmitted therefrom. The transmitted electromagnetic field may then be received by the receiver induction coil 260 to generate a corresponding electrical current.

Downstream from the fluid pump 232 and additive tank 228, dispenser nozzle 234 is mounted. Generally, dispenser nozzle 234 defines one or more output apertures for additive dispensing assembly 202 and is directed toward the drum 26 to guide or dispense a volume of the dryer additive into the space defined by the drum 26. In some embodiments, dispenser nozzle 234 is mounted proximal to or on interior surface 206. For instance, dispenser nozzle 234 may be mounted to assembly panel 214, as shown. Alternatively, dispenser nozzle 234 may be mounted apart from assembly panel 214 (e.g., rearward therefrom within internal cavity 212). In some such embodiments, one or more holes are defined through assembly panel 214 to permit the spray of liquid or dryer additive into the space defined by drum 26.

Optionally, dispenser nozzle 234 may include or be provided as an atomizer nozzle. Fluid flowing through additive dispensing assembly 202 from additive tank 228 may thus be directed into drum 26 as an atomized misted flow of liquid or dryer additive.

In some embodiments, a check valve or one-way valve (e.g., second one-way valve 238) is mounted in fluid communication between fluid pump 232 and dispenser nozzle 234. In other words, a second one-way valve 238 may be disposed along the fluid path or conduit extending from fluid pump 232 to dispenser nozzle 234. Second one-way valve 238 may thus ensure a unidirectional flow of dryer additive from the fluid path downstream from fluid pump 232 (e.g., according to gravity or negative pressure generated at fluid pump 232).

Referring now to FIGS. 7 through 10, a door 200 and additive dispensing assembly 202 are illustrated according to other exemplary embodiments of the present disclosure. Specifically, FIGS. 7 through 10 provide various views of a door 200 (e.g., provided as or as part of door 33) to a laundry appliance (e.g., dryer appliance 10). FIGS. 8 through 10 illustrate portions of an additive dispensing assembly 202. Although described separately from the embodiments of FIGS. 3 through 6, it is understood that the embodiments described herein are not mutually exclusive. Moreover, except as otherwise indicated, the embodiments of FIGS. 7 through 10 may include the features of FIGS. 3 through 6, and vice versa.

In certain embodiments, a partially enclosed (e.g., U-shaped) pocket 262 formed from one or more fence walls defines internal cavity 212. For instance, pocket 262 may be pivotably mounted to door 200 (e.g., at inner panel 210) to rotate or pivot between a covered position (FIG. 7) and an uncovered position (FIG. 8). An interior fence wall 276 of pocket 262 may define at least a portion of interior surface 206. As shown, in the covered position, interior fence wall 276 may be engaged with a portion of inner panel 210 (e.g., at a suitable latch or clasp) such that interior fence wall 276 is held upright relative to the vertical direction V and access to internal cavity 212 is restricted. In turn, a user may be unable to pass a hand or object through the open end of the U-shaped pocket 262 to internal cavity 212. By contrast, in the uncovered position, a top end of interior fence wall 276 is spaced apart from inner panel 210 (e.g., at an angle between 20° and 90° relative to the vertical direction V) such that access to the internal cavity 212 is permitted. In turn, a user may be able to pass a hand or object through the open end of the U-shaped pocket 262 when door 200 is in an open position (or otherwise not fully closed).

When assembled, at least a portion of additive dispensing assembly 202 (e.g., additive tank 228, fluid pump 232, or dispenser nozzle 234) may be mounted to pocket 262. Thus, such a portion may pivot with pocket 262 between the covered and uncovered positions.

For instance, one or more portions of additive dispensing assembly 202 (e.g., additive tank 228 or fluid pump 232) may be secured to pocket 262 via a plurality of mounting features or mechanical fasteners. Additionally or alternatively, adhesive(s), snap-fit mechanisms, interference-fit mechanisms, or any suitable combination thereof may secure one or more portions of additive dispensing assembly 202 to pocket 262. One skilled in the art will appreciate that additive dispensing assembly 202 may be mounted using other mounting means according to alternative embodiments. In optional embodiments, additive tank 228 in particular is removably mounted within internal cavity 212 (e.g., to pocket 262). Thus, a user may selectively remove

additive tank 228 from door 200 in order to supply or refill the liquid or dryer additive within tank volume 230. A movable lid 264 may be provided on additive tank 228 to selectively block an opening to tank volume 230 such that removal of the lid 264 permits a user to access and refill tank volume 230, regardless of whether additive tank 228 is secured within internal cavity 212 or removed from internal cavity 212.

In some embodiments, a level sensor 270 is provided within or in communication with tank volume 230. In particular, level sensor 270 may be in wired or wireless communication with controller 256 and configured to detect if or when the amount of liquid or dryer additive within tank volume 230. As shown, level sensor 270 may include a magnetic element 272 (e.g., permanent magnet slug) movably disposed within tank volume 230. For instance, magnetic element 272 may be enclosed or supported within a floatable pod inside additive tank 228. Thus, the vertical position of magnetic element 272 within additive tank 228 (e.g., when internal cavity 212 is closed, such as when pocket 262 is in the covered position) may correspond (e.g., be correlated to and driven by) to the level of liquid or dryer additive. As the amount of liquid or dryer additive changes, the relative position of magnetic element 272 within tank volume 230 changes accordingly. A detection element 274 (e.g., reed switch) may be mounted or fixed at a predetermined position or level relative to additive tank 228 or tank volume 230. The predetermined level may correspond to a minimum level or volume of liquid or dryer additive within tank volume 230. Moreover, detection element 274 may be configured to detect (e.g., a magnetic field from) magnetic element 272. Thus, detection element 274 may detect a field or signal from magnetic element 272 in response to magnetic element 272 falling to the predetermined level.

This written description uses examples to disclose the invention, including the best mode, and also to enable any person skilled in the art to practice the invention, including making and using any devices or systems and performing any incorporated methods. The patentable scope of the invention is defined by the claims, and may include other examples that occur to those skilled in the art. Such other examples are intended to be within the scope of the claims if they include structural elements that do not differ from the literal language of the claims, or if they include equivalent structural elements with insubstantial differences from the literal languages of the claims.

What is claimed is:

1. A dryer appliance comprising:

a cabinet;

a drum rotatably mounted within the cabinet, the drum defining a space for the receipt of clothes for drying; a door movably mounted to the cabinet to selectively restrict access to the drum, the door comprising an inner panel directed toward the drum;

an additive dispensing assembly held on the door and configured to provide an additive mist to the drum, the additive dispensing assembly comprising an additive tank defining a tank volume to store a dryer additive therein,

a fluid pump in fluid communication with the additive tank to motivate a volume of the dryer additive therefrom, and

a dispenser nozzle directed toward the drum downstream from the fluid pump to guide the volume of the dryer additive into the space defined by the drum; and

a partially enclosed pocket defining an internal cavity and being pivotably mounted to the door to move between a covered position and an uncovered position, the partially enclosed pocket comprising an interior fence wall in selective contact with the inner panel, the interior fence wall defining at least a portion of the internal cavity and at least a portion of an interior surface of the door in the covered position,

wherein the additive tank and the fluid pump are housed within the internal cavity, and

wherein the dispenser nozzle is mounted on the interior fence wall to pivot therewith.

2. The dryer appliance of claim 1, wherein the fluid pump comprises a fluid cylinder and a reciprocating piston slidably disposed within the fluid cylinder.

3. The dryer appliance of claim 1, wherein the additive dispensing assembly further comprises a one-way valve mounted in fluid communication between the additive tank and the fluid pump.

4. The dryer appliance of claim 1, wherein the additive dispensing assembly further comprises a one-way valve mounted in fluid communication between the fluid pump and the dispenser nozzle.

5. The dryer appliance of claim 1, wherein the dispenser nozzle comprises an atomizer nozzle positioned in fluid communication between the fluid pump and the drum.

6. The dryer appliance of claim 1, further comprising: a transmitter induction coil mounted to the cabinet; and a receiver induction coil mounted to the door in electrical communication with the fluid pump, the receiver induction coil being inductively coupled to the transmitter induction coil to receive an electromagnetic field therefrom.

7. A laundry appliance comprising:

a cabinet;

a drum rotatably mounted within the cabinet, the drum defining a space for the receipt of clothes;

a door movably mounted to the cabinet to selectively restrict access to the drum, the door defining an internal cavity between an exterior surface and an interior surface, the interior surface being at least partially defined by an inner panel directed toward the drum; an additive dispensing assembly disposed within the internal cavity and configured to provide an additive mist to the drum, the additive dispensing assembly comprising

an additive tank defining a tank volume to store a liquid additive therein, the additive tank being removably mounted within the internal cavity,

a fluid pump in fluid communication with the additive tank to motivate a volume of the liquid additive therefrom,

a dispenser nozzle directed toward the drum downstream from the fluid pump to guide the volume of the liquid additive into the space defined by the drum, and

a one-way valve in fluid communication between the additive tank and the dispenser nozzle to permit the volume of liquid additive to the dispenser nozzle from the additive tank; and

a partially enclosed pocket defining the internal cavity and being pivotably mounted to the door to move between a covered position and an uncovered position, the partially enclosed pocket comprising an interior fence wall in selective contact with the inner panel, the interior fence wall defining at least a portion of the

11

internal cavity and at least a portion of an interior surface of the door in the covered position, wherein the additive tank, one-way valve, and the fluid pump are housed within the internal cavity, and wherein the dispenser nozzle is mounted on the interior fence wall to pivot therewith.

8. The laundry appliance of claim 7, wherein the fluid pump comprises a fluid cylinder and a reciprocating piston slidably disposed within the fluid cylinder.

9. The laundry appliance of claim 7, wherein the one-way valve is a first one-way valve, and wherein the laundry appliance further comprises a second one-way valve mounted in fluid communication between the additive tank and the fluid pump.

10. The laundry appliance of claim 7, wherein the dispenser nozzle comprises an atomizer nozzle positioned in fluid communication between the fluid pump and the drum.

11. The laundry appliance of claim 7, further comprising: a transmitter induction coil mounted to the cabinet; and a receiver induction coil mounted to the door in electrical communication with the fluid pump, the receiver induction coil being inductively coupled to the transmitter induction coil to receive an electromagnetic field therefrom.

12. A laundry appliance comprising:

a cabinet; a drum rotatably mounted within the cabinet, the drum defining a space for the receipt of clothes; a door movably mounted to the cabinet to selectively restrict access to the drum, the door defining an internal cavity between an exterior surface and an interior surface, the interior surface being at least partially defined by an inner panel directed toward the drum; an additive dispensing assembly disposed within the internal cavity and configured to provide an additive mist to the drum, the additive dispensing assembly comprising an additive tank defining a tank volume to store a liquid additive therein, the additive tank being removably mounted within the internal cavity,

12

a fluid pump in fluid communication with the additive tank to motivate a volume of the liquid additive therefrom,

an atomizer nozzle directed toward the drum downstream from the fluid pump to guide the volume of the liquid additive into the space defined by the drum, and

a one-way valve in fluid communication between the additive tank and the atomizer nozzle to permit the volume of liquid additive to the atomizer nozzle from the additive tank; and

a partially enclosed pocket defining the internal cavity and being pivotably mounted to the door to move inward toward the drum between a covered position and an uncovered position, the partially enclosed pocket comprising an interior fence wall in selective contact with the inner panel to enclose the internal cavity in the covered position, the interior fence wall defining at least a portion of the internal cavity and at least a portion of an interior surface of the door in the covered position,

wherein the additive tank, one-way valve, and the fluid pump are housed within the internal cavity, and wherein the atomizer nozzle is mounted on the interior fence wall to pivot therewith.

13. The laundry appliance of claim 12, wherein the fluid pump comprises a fluid cylinder and a reciprocating piston slidably disposed within the fluid cylinder.

14. The laundry appliance of claim 12, wherein the one-way valve is a first one-way valve, and wherein the laundry appliance further comprises a second one-way valve mounted in fluid communication between the additive tank and the fluid pump.

15. The laundry appliance of claim 12, further comprising:

a transmitter induction coil mounted to the cabinet; and a receiver induction coil mounted to the door in electrical communication with the fluid pump, the receiver induction coil being inductively coupled to the transmitter induction coil to receive an electromagnetic field therefrom.
